UNITED STATES PATENT OFFICE.

SAMUEL RUBEN, OF NEW YORK, N. Y.

APPARATUS FOR THERAPEUTIC APPLICATIONS.

Application filed January 17, 1924. Serial No. 696,853.

To all whom it may concern:

Be it known that I, SAMUEL RUBEN, citizen of the United States, and resident of New York city, in the county of New York and State of New York, have invented certain new and useful Improvements in Apparatus for Therapeutic Applications, of which the following is a specification.

This invention relates to an apparatus for therapeutic applications; and more particularly, it relates to a therapy apparatus for the application of infra red radiations.

It has been known for centuries that radiant energy has a high therapeutic value; and it has been found that it is the infra red rays of that energy, of long wave length and high intensity that represent by far the greater part of the value. These rays applied to body tissue penetrate it deeply and create a constructive and stimulating warmth thereof. They are thus converted into heat and produce an hyperemia of the treated tissue, which is highly effective in restoring tissue to normal healthy condition.

One of the objects of this invention is to provide a generator of infra red rays which converts a high percentage of the applied energy into infra red radiations, and means for therapeutically applying them so as to give the patient a minimum of discomfort from the sensation of heat, thus permitting the application in greater intensity and over prolonged periods.

In the prior art, the devices most widely employed for the generation of infra red rays consist of low pressure lamps containing incandescent filaments, efficient in the production of short wave length radiations in the visible spectrum, but of limited efficiency in the radiation of the long wave length infra red rays, which latter pass through the silica glass walls of the lamp in minute volume only.

According to the terms of this invention, infra red rays are generated by the application of heat from a contained heating element, to the walls of a vessel composed of glass and coated exteriorly with a black material having a high thermal radiation constant, such, for instance, as deflocculated graphite, in which, at operating temperatures, no chemical or thermo-mechanical changes occur. The short wave radiations, which are in the visible spectrum and are practically the only rays passing from the heating element, through the walls, are very

largely absorbed by the black coating, there transformed and then radiated from its exterior surface as infra red rays of long wave length, characteristic of black body 60 radiations. By this means infra red rays of high intensity and deep penetrating power are obtained.

One of the preferred types of generator body is comprised of a boron-silica glass 65 tubing shaped into any desired form, such, for instance, as a spiral coil, with a thermal activating unit within it, and its area opposite to the surface to be treated, blackened, as described, or in any other suitable manner, as by the deposition of copper which is then oxidized. If desired, previous to sealing, the tube can be filled with a highly conducting gas, such as helium. A suitable heat wave reflecting surface is provided on the 70 side of the uncoated area of the vessel surface, from which some of the infra red rays are reflected, and a considerable volume of the heat waves radiated from the uncoated portion of the walls is reflected back to and 75 through the vessel to the blackened surface, from which it is radiated as infra red rays. That portion of the surface to be blackened is preferably closely furrowed, to obtain a 80 maximum radiation surface.

The heat effects generated by these radiations at the nerve terminals at the skin surface have heretofore prevented the intense or long continued application of infra red rays, the distress thereby occasioned the patient, making such treatment often impracticable. I provide a means by which this 90 objection is overcome; that is by carrying off the heated air from the skin surface under treatment, by a cooling medium, such as a blast of air, which in no way decreases the radiant activity or the power of penetration of these rays, and permits deep 95 therapeutic applications without the limitations heretofore existing.

In order to afford a full understanding of the principles of the invention, one embodiment thereof in a specially practicable form is illustrated in the accompanying drawings, and is hereinafter described in detail for 105 the sake of a concrete illustrative example; but it is to be understood that the invention is not limited to this particular arrangement.

In the drawings referred to, 110
Fig. 1 shows partly in elevation and partly in section an apparatus of this inven-

tion, Fig. 2, showing the surface-blackened infra red generator element, a cross section taken at 3-3, being indicated by Fig. 3.

Referring more particularly to Fig. 1, 5 1 represents a glass tube coiled in spiral form, its surface being partially coated with deflocculated graphite. Within the tube is a coil of high resistance wire connected in an electrical circuit by leads 3 and 4. On 10 the convex side of the spiral coil 1, is a reflector R, the concave surface of which is highly polished, attached to a heat insulating tube 5, the whole being mounted on stand S, and angularly adjustable at A. 15 Blower B, is also mounted on stand S, an air outlet being at N.

In operation, as current is supplied to the heating coil within glass coil 1, the short 20 length heat waves discharge through the walls of coil 1, to the outer or blackened surface, by which they are converted almost wholly into the long length infra red rays which radiate outwardly. A portion of the 25 heat waves discharging through the uncoated section of the coil wall are reflected by the reflector back into the coil 1, and converted by the black surface into infra red rays. To prevent the discomforting sensation of excessive heat at the nerve terminals 30 in the surface area upon which the rays are directed, a blast of air from blower B, is directed through nozzle N, upon that area, in this way neutralizing the sensation of heat by carrying away the heated air.

35 What I claim is:

1. An apparatus for the production of infra red rays, comprising a glass vessel having therewithin an element adapted to emit radiations of short wave lengths, a 40 black material being in molecular contact with the surface of the wall of said vessel.

2. A therapy apparatus comprising a glass vessel having therewithin an element adapted to emit radiations of short wave 45 lengths, and a source of infra red radiations consisting of a black material in molecular contact with the outer surface of the wall of said vessel.

3. A therapy apparatus comprising a 50 glass vessel having therewithin an element adapted to emit radiations of short wave

lengths, and a coating of deflocculated graphite upon the outer surface of said vessel, in molecular contact therewith.

4. A therapy apparatus comprising a 55 glass vessel having therewithin an element adapted to emit radiations of short wave lengths, and a coating of black material upon the outer surface of said vessel, in molecular contact therewith, in combination with means for discharging a column 60 of air across the path of radiations from said black material.

5. A source of infra red radiations comprising a receptacle composed of an amorphous compound of boron and silica, and containing a heating element therewithin, the outer surface of said receptacle having 65 a black material in molecular contact therewith.

6. A source of infra red radiations, comprising a receptacle composed of an amorphous compound of boron and silica, and containing therewithin a heating element, the outer surface of said receptacle having 70 75 a coating of deflocculated graphite in molecular contact therewith.

7. An apparatus for therapeutic applications, comprising, in combination, a receptacle composed of an amorphous compound 80 of boron and silica, and containing a high resistance wire connected in an electrical circuit, the outer surface of said receptacle being in molecular contact with a black material, and means for discharging a column 85 of air across the path of radiations from said material.

8. An apparatus for therapeutic applications, comprising a receptacle comprising a tubing composed of an amorphous compound of boron and silica, arranged in the form of a spiral, and containing a high resistance wire connected in an electrical circuit, the outer surface of said tubing having 90 a coating of deflocculated graphite in molecular contact therewith, substantially as described.

Signed at New York, in the county of New York and State of New York, this 12th day of January A. D. 1924.

SAMUEL RUBEN.
